US0D1098239S

(12) **United States Design Patent** (10) Patent No.: **US D1,098,239 S**
(45) Date of Patent: ** Oct. 14, 2025

(54) **CAMERA**

(71) Applicant: **Huizhou Shifengda Technology Co., Ltd.**, Huizhou (CN)

(72) Inventor: **Aiyi Wang**, Guangdong (CN)

(**) Term: **15 Years**

(21) Appl. No.: **35/522,977**

(22) Filed: **Sep. 11, 2024**

(80) **Hague Agreement Data**

Int. Filing Date: **Sep. 11, 2024**

Int. Reg. No.: **DM/240244**

Int. Reg. Date: **Sep. 11, 2024**

Int. Reg. Pub. Date: **Nov. 15, 2024**

(30) **Foreign Application Priority Data**

Apr. 10, 2024 (CN) 202430197873.0

(51) **LOC (15) Cl.** **16-01**

(52) **U.S. Cl.**
